UNITED STATES PATENT OFFICE.

EDWIN S. TRIMBLE, OF ATCHISON, KANSAS.

COLLAPSIBLE CHICKEN COOP.

Application filed November 6, 1925. Serial No. 67,402.

This invention relates to improvements in chicken coops and has for its principal object to provide one which is of such construction as to permit the same being compactly folded for shipping or storing purposes, the same being further adapted to be readily and easily set up in position for use.

A further object of the invention is to provide a collapsible chicken coop wherein the same includes a bottom, foldable ends and sides, and a top, the top being associated with the respective ends for facilitating the upward swinging movement of the end members to an upright position simultaneous with the raising of the top whereby the side members may be swung upwardly to an upright position, additional means being provided on the top for cooperation with the side members for holding the same in their upright position whereby the chicken coop will be maintained in its assembled position for use in housing the poultry to be shipped.

A further object is to provide a collapsible chicken coop wherein a swinging partition is arranged in the intermediate portion thereof for the purpose of separating the mixed poultry, the top of the coop being provided with a centrally located opening and a slideable closure therefor, the opening being so arranged as to permit access to either of the compartments formed when the partition is disposed in its upright position.

A still further object is to provide a collapsible chicken coop of the above mentioned character which is simple in construction, inexpensive, strong and durable and further well adapted to the purpose for which it is designed.

Other objects and advantages of the invention will become apparent during the course of the following description taken in connection with the accompanying drawings.

In the accompanying drawings forming part of the present application and in which like numerals designate like parts throughout the same:

Figure 1 is a top plan view of the chicken coop embodying my invention showing the same in its assembled position.

Figure 2 is a side elevation thereof.

Figure 3 is an end elevation.

Figure 4 is a vertical section taken

approximately on line 4—4 of Figure 2 looking in the direction of the arrows.

Figure 5 is a side elevation showing the coop in its partially collapsed position.

Figure 6 is a fragmentary detail perspective of the spring attached forming a part of the present invention, and

Figure 7 is a detail sectional view taken approximately on line 7—7 of Figure 1, showing the manner in which the hooked ends of the intermediate longitudinally extending rods forming a part of the top of the coop engage the upper edge of the end members.

In the drawings, wherein for the purpose of illustration is shown the preferred embodiment of my invention, the numeral 1 designates generally my improved collapsible chicken coop, the same comprising the substantially rectangular base or bottom 2 which is formed preferably of wood. Extending longitudinally along the bottom of the wooden base 2 adjacent the respective side edges of the base as well as along the intermediate portion thereof are the rods 3. Transversely extending rods 4 are also arranged on the bottom of the wooden base adjacent the respective ends thereof as well as at the intermediate portion and all of these rods are connected together at their intersections in any suitable manner such as by spot welding. Extending upwardly from each of the longitudinally extending side wires are the hooks 5, and similar hooks 6 extend upwardly from the respective transversely extending end rods. This construction is more clearly illustrated in Figures 3, 4 and 5 of the drawing. The upper free ends of the hooks are disposed above the upper surface of the wooden base or bottom 2, and the purpose thereof will herein-after be more fully described.

The coop further includes the end members 7 and 8 respectively. Each of the end members includes the frame 9 formed from a single elongated strand of wire. A series of spaced vertically arranged rods 10 are spot welded or otherwise secured to the upper and lower portions of the frame of each of the end members and intersecting these rods are the horizontally arranged rods 11, the same also being spot welded or otherwise secured to the respective sides of each of the frames and further being spot

welded to the vertical rods at the point of intersection therewith. Additional rods 12 are disposed diagonally across the vertical rods 10 in the manner as more clearly illustrated in Figure 3.

The end members 7 and 8 are hingedly supported on the respective ends of the base or bottom 2 and to this end the hooks 6 which extend upwardly from the transversely extending end rods 4 engage the bottom portions of the frames of the respective end members as also clearly illustrated in Figure 3. As is shown in Figure 3, the ends of the uppermost horizontally extending rods 11 are not secured to the respective sides of the frame of each of the end members, but are spaced therefrom and are secured to the outermost vertical rods and the purpose of this arrangement will be presently apparent.

The side members forming a part of the coop are designated by the numerals 13 and 14 respectively, and each of the side members comprises a frame 15 formed of an elongated strand of wire. Spaced vertically and horizontally arranged rods 16 and 17 respectively are arranged between the top and bottom and the respective sides or ends respectively of each of the frames, and these rods are spot welded or otherwise secured at their ends to the frame as well as at their intersections with each other.

The side members are also hingedly supported at their lower edges to the respective sides of the base or bottom 2, and the upwardly extending hooks 5 associated with the longitudinally extending rods 3 adjacent the side edges of the base engage the lower portions of the frames of each of the side members to afford the aforementioned hinged connections. The side members are of such height as to permit the upper edges of the frames thereof to be disposed in slight spaced relation with respect to each other when the side members are swung inwardly and are disposed on top of the upper surface of the base or bottom 2.

The top for the coop is designated generally by the numeral 18, and the same includes the outermost pair of rods 19 and the intermediate pair of longitudinally extending rods 20 as well as a series of spaced transversely extending rods 21. Each of the outermost rods 19 is of relatively great length and the ends thereof are bent back upon themselves and the free end portions are disposed in parallel spaced relation with respect to the adjacent intermediate portion to provide what I term as end loops 22. The free ends of the elongated rods 19 are disposed in abutting relation and are welded or otherwise secured to the intermediate portion of the rod as at 23. This construction is clearly illustrated in Figure 5 and the purpose of forming the loops which are

of an elongated form or shape will be hereinafter fully described. The free ends of the intermediate longitudinally extending rods 20 terminate in the hooks 24 and these hooks are adapted for detachable engagement with the upper portions of the frames of the respective end members 8 and 7 in the manner as clearly illustrated in Figure 7.

The top 18 is further provided with an enlarged central opening 25 whereby access to the coop when the latter is assembled may be easily had. A closure 26 is slidably mounted on the top 18 and may be readily and easily slid over the opening to cover the same and this is accomplished by having the longitudinally extending rods 27 of the closure provided at their ends with hooks which slidably engage the transversely extending rods 28, the latter extending between the outermost pair of rods 19, and being of a heavier gage than the other transversely extending rods 21 in the manner as more clearly illustrated in Figure 1.

As clearly illustrated in Figures 2 and 5 of the drawings, the upper portions of the end members 7 and 8 are slidably associated with the elongated loop 22 formed at the end of the rods 19, and in this manner, a connection between the top and the end members is provided whereby the same are adapted for simultaneous operation as will be presently described.

For the purpose of holding the upper free portions of the side members in an upright position when the coop is assembled, I provide spring wire or rod 29, the same extending transversely across the intermediate portion of the top and being spot welded or otherwise secured to the intermediate portions of the longitudinally extending rods 20 at their points of intersection. Each end of the spring wire or rod 29 is bent downwardly as at 30 and thence upwardly as at 31 and thence laterally as at 32. The laterally extending portions 32 terminating in the angularly disposed portions 33, and as is clearly illustrated in Figure 6, the angularly disposed portions 33 extend beyond the sides of the tops so as to provide a suitable handle. By forming each end of the spring wire in the manner as above described, a pair of spring catches will be provided. The upwardly disposed portions 31 will engage the upper portions of the frame of the respective side members and hold the same in abutting relation with respect to the looped rods 19 which extend along the sides of the top 18.

The coop is further provided with a central partition designated generally by the numeral 34, and the same includes a frame 35 and the horizontally and vertically arranged rods 36 and 37 respectively, these rods being also arranged in spaced relation and being furthermore secured to the frame

as well as at their intersections in a manner similar to that in which the rods of the other aforementioned frames are secured. The partition 34 is hingedly secured at its bottom to the intermediate portion of the base or bottom 2, and to this end, suitable hooks 38, similar to the hooks 5 and 6 extend upwardly from the transversely extending rods disposed adjacent the bottom of the base, it being understood of course that suitable openings are provided in the base to accommodate the hooks 38, and the latter engage the bottom portion of the frame 35 as shown clearly in Figure 4. The partition is of same shape as the end members of the coop and is adapted to fold or swing in either direction.

The downwardly disposed portions 30 of the spring rod or wire 29 cooperate with the inwardly disposed fingers 39 which are arranged at the intermediate portions of the looped rods 19 in supporting the partition in its vertical position in the manner as clearly illustrated in Figure 6. The inwardly extending fingers 39 furthermore frictionally engage the bottom of the upper portions of the frames of the side members to assist in holding the latter in their proper positions.

In this manner, the partition will provide a twofold purpose, in one instance the partition permits the coop to be divided into separate compartments whereby a mixed shipment of poultry may be placed within the respective compartments of the coop, the central opening 25 arranged in the top being so positioned as to permit access to either of the compartments when the partition is in use. Furthermore, the partitions may be used as an additional means for bracing and supporting the coop when the latter is assembled.

When the coop is not in use, or whenever it is desired to fold or otherwise collapse the same in a compact manner, the spring catches are disengaged from engagement with the partition, and the latter is caused to swing downwardly so as to lie flat against the upper surface of the base or bottom of the coop. The side members 13 and 14 are then disengaged from the spring catches and the inwardly extending fingers 39 and are then swung inwardly in the manner as indicated by the dotted lines in Figure 4 so as to also rest upon the upper surface of the base or bottom.

The upper portions of the respective end members are then moved inwardly toward each other so that the upper portion of each of the frames of each of the end members will slide in the looped portions 22 of the top 18 and by pushing the top downwardly, the end members will simultaneously swing inwardly and downwardly in the manner as indicated by the arrows in Figure 5, so that

the end members will overlap the side members and the top 18 will then lie flat upon the superimposed side and end members. In this manner, the crates or coops will be collapsed to provide a compact arrangement, and when in this condition, the coops may be easily and readily handled or transported, and will not occupy any considerable amount of space.

Whenever it is desired to use the coop, the same can be readily and easily assembled in the manner as is obvious from the construction shown in the drawings, and when once assembled, there will be no possibility of the parts accidentally becoming disengaged and causing the accidental collapsing of the coop.

The simplicity of my improved coop enables the same to be manufactured at a very low cost and by constructing the same of rods so as to provide an open work structure, the coop is rendered strong and durable.

While I have shown the preferred embodiment of my invention it is to be understood that minor changes coming within the spirit of the invention and the scope of the appended claims may be resorted to without departing from the spirit of the invention and the scope of the appended claims.

Having thus described the invention, what I claim as new is:

1. A collapsible coop comprising a base, end and side members hingedly secured at their lower portions to the base, and a top, said top being operatively connected with the upper free portions of the end members whereby the same are adapted for simultaneous operation, a central partition hingedly secured at its lower portion on the base, and means for holding the side and end members and the partition in their upright position.

2. A collapsible coop comprising a base, end and side members hingedly secured at their lower portions to the base, and a top, said top being operatively connected with the upper free portions of the end members whereby the same are adapted for simultaneous operation, a central partition hingedly secured at its lower portion on the base, and means for holding the side and end members and the partition in their upright position, said last mentioned means comprising catches carried by the top.

3. A collapsible coop comprising a base, end and side members hingedly secured at their lower portions to the base, a top, said top being operatively connected with the upper free portions of the end members whereby the same are adapted for simultaneous operation, a central partition hingedly secured at its lower portion on the base, and means for holding the side and end members and the partition in their upright position, said means comprising spring catches carried by the top and adapted to

- engage the upper portion of the partition on one side thereof, and inwardly extending fingers carried by the top and adapted to engage the opposite sides of the partition.
- 5 4. A collapsible coop comprising a base, end and side members hingedly secured at their lower portions to the base, a top, said top being provided at its sides adjacent the respective ends thereof with looped portions 10 in which the upper portions of the respective end members are adapted to slide whereby an operative connection between the top and the free portions of the end members is provided to effect the simultaneous actua-

tion of the top and the end members, a central partition hingedly secured at its lower portion on the base, and means for holding the coop in its assembled position, said means comprising a spring wire extending transversely across the intermediate portion of the top and being secured thereto, each end of the spring wire being bent downwardly and thence upwardly, and thence laterally to provide spring catches adapted for engagement with the partition and the intermediate portions of the side members. 15 20 25

In testimony whereof I affix my signature
EDWIN S. TRIMBLE.
